(57) **CLAIM**

The ornamental design for an elastomeric condenser plug, as shown and described.

DESCRIPTION

FIG. 1 is a perspective view of a new and ornamental design for an elastomeric condenser plug;

FIG. 2 is a front view thereof;

FIG. 3 is a rear view thereof;

FIG. 4 is a left side view thereof;

FIG. 5 is a right side view thereof;

FIG. 6 is a top plan thereof; and

FIG. 7 is a bottom plan thereof.

FIG. 8 is a perspective view of a second embodiment of a new and ornamental design for an elastomeric condenser plug;

FIG. 9 is a front view thereof;

FIG. 10 is a rear view thereof;

FIG. 11 is a left side view thereof;

FIG. 12 is a right side view thereof;

FIG. 13 is a top plan thereof; and,

FIG. 14 is a bottom plan thereof.

The broken lines in FIGS. 6 and 13 are for the purpose of illustrating environmental structure and form no part of the claimed design.
